(57) **CLAIM**

The ornamental design for a door push plate, as shown and described.

DESCRIPTION

FIG 1 is a front elevation view of a first embodiment of a door push plate showing my new design;

FIG. 2 is a top plan view thereof;

FIG. 3 is a bottom plan view thereof;

FIG. 4 is a rear elevation view thereof;

FIG. 5 is a left side elevation view thereof, the right side elevation view being a mirror image;

FIG. 6 is a front elevation view of a second embodiment of a door push plate showing my new design;

FIG. 7 is a top plan view thereof;

FIG. 8 is a bottom plan view thereof;

FIG. 9 is a rear elevation view thereof; and,

FIG. 10 is a left side elevation view thereof, the right side elevation view being a mirror image.

The broken lines in the drawings illustrate portions of the door push plate which form no part of the claimed design.

1 Claim, 4 Drawing Sheets
